UNITED STATES PATENT OFFICE.

JOHN A. CARLSTEDT, OF BROOKLYN, NEW YORK, ASSIGNOR TO GEORGE FRINK SPENCER, OF NEWARK, NEW JERSEY.

DEVICE FOR FORMING ANNULAR SHEET-METAL RINGS.

SPECIFICATION forming part of Letters Patent No. 595,287, dated December 14, 1897.

Application filed April 27, 1897. Serial No. 634,079. (No model.)

To all whom it may concern:

Be it known that I, JOHN A. CARLSTEDT, a citizen of the United States, residing at Brooklyn, in the county of Kings and State of New York, have invented certain new and useful Improvements in Attachments or Devices for Forming Annular Sheet-Metal Rings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates more particularly to a novel construction of apparatus or device for forming circular metal rings from a continuous piece of flat and straight sheet metal, said apparatus being intended for use in connection with that class of machines known as "beading-machines."

The present invention has for its primary object to provide an apparatus or device of the nature hereinafter specified, working in conjunction with the beading-rolls of a beading-machine, whereby a straight and flat piece of sheet metal which is fed between said rolls is suitably ornamented and beaded and at the same time is forced into the shape of a flat annular ring.

Heretofore flat rings of sheet metal were cut in short pieces by means of a hand-shears, being suitably curved, and such pieces, usually four, five, or six of them, were then placed end to end and soldered together to form the completed flat annular ring, or such pieces had to be forced from the blank of sheet metal by means of suitable dies and then soldered end to end, as stated. This method of producing flat rings of comparatively large diameter was slow and tedious, as well as expensive.

A further object of this invention, therefore, is to obviate these objections and provide a band or ring having a better and more finished appearance.

With these several objects in view the invention consists in the novel construction of attachment or device for forming annular rings of sheet metal, as well as in the novel

arrangement and combination of same with the rolls of a beading-machine.

The invention consists, furthermore, in the details of construction and the peculiar combinations of the parts of the apparatus or device forming my invention, all of which will be hereinafter fully described, and finally embodied in the clauses of the claim.

The invention is clearly illustrated in the accompanying drawings, in which—

Figure 1 is a perspective view of a beading-machine, illustrating in connection with the same my novel form of ring-forming device or apparatus embodying the principles of my invention. Fig. 2 is a top or plan view of the apparatus or device. Fig. 3 is an end view of the same when looking in the direction of arrow *x* in Fig. 2; and Fig. 4 is a cross-section, taken on line *y* *y* in said Fig. 2, when looking in the direction of arrow *y*'. Fig. 5 is a bottom view of the ring-forming device or attachment, and Fig. 6 is a detail view illustrating a cross-section of the lower bead-roll axle and that portion of the framework of the beading-machine and one means of securing the ring-forming device or attachment in its operative position on said portion of the framework of the beading-machine.

Similar letters of reference are employed in all of the above-described views to indicate corresponding parts.

In the accompanying drawings, *A* indicates the general construction of a beading-machine comprising the usual frame portions *a* and *a'* and operating mechanism *a*² for operating the journals *b* and *b'*, which are respectively provided with the feed-rolls *b*² and *b*³, as clearly illustrated in Fig. 1. My novel construction of device or apparatus for forming a flat strip of sheet metal into a circular shape as it passes between said rolls *b*² and *b*³ consists, essentially, of a flat plate *c*, forming a table, and has an opening *c*' through which the contacting surfaces of the rolls *b*² and *b*³ project for properly forcing the sheet-metal band *d* over the upper surface of the table *c* when the machine is in operation. The under side of said table *c* may be provided with suitably arranged strengthening-ribs *c*² and a pair of clamping-leaves *c*³, having the curved surfaces *c*⁴, adapted to be fitted around and em-

brace the frame portion a' of the beading-machine A and clamped in its operative position by means of a bolt e and nut e' passing through the perforated ears or lugs c^5 on said 5 clamping-leaves c^3 , all of which is clearly illustrated in Fig. 6 of the drawings.

Secured upon the upper face of the table c , by means of screws f^2 passing through a perforated flange f' , or in any other well-known 10 manner, is a guide f , having the upwardly-extending guiding edges f^3 , extending back contiguous to the edge c^6 of the opening c' in the plate or table c and terminating in a suitably-constructed bearing portion f^4 , as clearly 15 shown in Figs. 2, 3, and 6. Said guide is also provided with an extra guiding lip or flange f^5 , projecting at a right angle from said edges f^3 , said lip or flange being approximately parallel to the upper surface of said table, where- 20 by a strip of sheet metal can be laid on its flat side on said table and passed beneath said lip or flange f^5 , as clearly illustrated in Fig. 1.

When a wide strip or band of sheet metal is to be formed into an annular flat ring, a 25 second guide h may be employed, said guide having the $\square$ -shaped guiding portion h' and being adjustably secured by means of screws or bolts h^2 and nuts h^3 in a pair of slots c' in the plate or table c , as clearly represented in 30 Figs. 1, 2, 4, and 5. Thus it will be evident that said guide h may be adjusted so that its guiding portion h' will readily grip the edge of the sheet metal, and said metal thus passing between the two guides f and h is prevented 35 from buckling, as will be understood.

As will be more especially seen from an inspection of Figs. 2 and 3, the said table or plate c is provided with a suitable scale or index, as c^{11} , and adjustably arranged above 40 said plate c , by means of screws or bolts g and g' passing through suitable slots c^8 and c^9 in the table or plate c , is a plate i , and secured in like manner to the under surface of said table or plate c is a second plate j . The plate 45 i is slightly raised in the middle and has secured thereto in any well-known manner a pair of guide-plates i' and i^2 , connected means of a U -shaped guiding-surface i^3 , against which the edge of the sheet-metal strip or band d is passed as it is fed from the rolls b^2 and b^3 between said guide-plates i' and i^2 . At one end of said plate i^2 is an upright or post i^4 , arranged in a bearing portion f^6 of the guide f , whereby when the bolts or 50 screws g and g' are slightly loosened the plates i and j , as well as the guide-plates i' and i^2 , connected with the plate i , can be moved laterally by means of a suitable rod i^5 and handle i^6 and a pointer i^7 on a projection or other 55 suitable part of the guide-plate i^2 , set at any desired point on the scale c^{11} .

As an extra precaution to prevent the metal from buckling a second plate k , having a U -shaped guiding portion k' , may be employed, 60 said plate having a perforated projection k^2 and a screw or bolt k^3 and nut k^4 , passing through a slot c^{10} in the plate or table c ,

whereby said guide k can be adjusted and secured at the proper angle on the upper surface of the table c , as will be clearly understood. 70

To prevent the end of the strip or band of metal from passing down through the opening c' in the table or plate c , the guide-plate i' is provided with a lip or projection, as i^8 , 75 which extends over said opening, as shown in Figs. 2 and 5, and to a position in close proximity to the contacting surfaces of the two rolls b^2 and b^3 .

The operation of the hereinabove-described 80 device or apparatus is very simple and will be readily understood, being perfectly operative for the purposes set forth of making from a continuous flat strip or band of sheet metal flat annular rings of different sizes and 85 widths.

It will be understood that changes may be made in the arrangements and combinations of the several parts, as well as in the details of construction thereof, without departing 90 from the scope of my present invention. Hence I do not limit my invention to the exact arrangements and combinations of the parts herein described, and illustrated in the 95 accompanying drawings.

Having thus described my invention, what I claim is—

1. In a beading or similar machine, the combination, with the rollers thereof, of a device for forming annular flat rings from a strip of 100 sheet metal, comprising a table or plate, adapted to be attached to said machine, a guide on said table or plate, an upwardly-extending guiding edge on said guide, and a lip or flange at a right angle to said guiding edge 105 and approximately parallel to the face of the table or plate, whereby said strip of sheet metal can be laid on its flat side on said table and fed beneath said lip or flange, and means directly back of said rolls for deflecting 110 said metal strip to one side to form a flat circular bead, substantially as and for the purposes set forth.

2. In a beading or similar machine, the combination, with the rollers thereof, of a device 115 for forming annular flat rings from a strip of sheet metal, comprising a table or plate, adapted to be attached to said machine, a guide on said table or plate, an upwardly-extending guiding edge on said guide, and a lip 120 or flange at a right angle to said guiding edge and approximately parallel to the face of the table or plate, whereby said strip of sheet metal can be laid on its flat side on said table and fed beneath said lip or flange, and a $\square$ -shaped guide-plate directly back of said rolls 125 for deflecting said metal strip to one side and prevent it from buckling, to form a flat circular band, substantially as and for the purposes set forth.

3. In a beading or similar machine, the combination, with the rollers thereof, of a device for forming annular flat rings from a strip of sheet metal, comprising a table or plate,

- adapted to be attached to said machine, a guide on said table or plate, an upwardly-extending guiding edge on said guide, and a lip or flange at a right angle to said guiding edge 5 and approximately parallel to the face of the table or plate, whereby said strip of sheet metal can be laid on its flat side on said table and fed beneath said lip or flange, and an adjustable $\square$ -shaped guide-plate directly 10 back of said rolls for deflecting said metal strip to one side and prevent it from buckling, to form a flat circular band, substantially as and for the purposes set forth.
4. In a beading or similar machine, the combination, with the rollers thereof, of a device for forming annular flat rings from a strip of sheet metal, comprising a table or plate, adapted to be attached to said machine, a guide on said table or plate, an upwardly-extending guiding edge on said guide, and a lip or flange at a right angle to said guiding edge and approximately parallel to the face of the table or plate, an adjustable guide h 15 on said table having a $\square$ -shaped guiding portion h' , whereby the strip of sheet metal can be laid on its flat side on said table and fed beneath the lip or flange of the one guide and between the $\square$ -shaped guiding portion of said adjustable guide, to prevent buckling of the 20 sheet metal, and means directly back of said rolls for deflecting said metal strip to one side and prevent it from buckling, to form a flat circular band, substantially as and for the purposes set forth.
5. In a beading or similar machine, the combination, with the rollers thereof, of a device for forming annular flat rings from a strip of sheet metal, comprising a table or plate adapted to be attached to said machine, a guide on said table or plate, an upwardly-extending guiding edge on said guide, and a lip or flange at a right angle to said guiding edge and approximately parallel to the face of the table or plate, an adjustable guide h on said 25 table having a $\square$ -shaped guiding portion h' , whereby the strip of sheet metal can be laid on its flat side on said table and fed beneath the lip or flange of said one guide and between the $\square$ -shaped guiding portion of said adjustable guide, to prevent buckling of the 30 sheet metal, and a $\square$ -shaped guide-plate directly back of said rolls for deflecting said metal strip to one side and prevent it from buckling, to form a flat circular band, substantially as and for the purposes set forth.
6. The herein-described device or apparatus for forming annular rings of flat metal, consisting, essentially, of a table or plate c , having an opening c' , a scale on said table or plate, a guide pivotally connected with said table or plate, an index-point on said guide, and means for adjusting said guide, substantially as and for the purposes set forth.
7. The herein-described device or apparatus for forming annular rings of flat metal, consisting, essentially, of a plate or table c having an opening c' , a guide f on said table, a guiding edge f^3 thereon, a bearing portion f^4 and a guiding-flange f^5 at a right angle to said edge f^3 and approximately parallel to the upper surface of said table, whereby a strip of sheet metal can be laid on its flat side on said table and fed beneath said flange f^5 , and a guide at the opposite side of said opening c' , pivotally connected with said table or plate, substantially as and for the purposes set forth.
8. The herein-described device or apparatus for forming annular rings of flat metal, consisting, essentially, of a plate or table c having an opening c' , a guide f on said table, having a guiding edge f^3 , a bearing portion f^4 and guiding-flange f^5 , a scale on said table or plate, a guide pivotally connected with said table or plate, an index-point on said guide, and means for adjusting said guide, substantially as and for the purposes set forth.
9. The herein-described device or apparatus for forming annular rings of flat metal, consisting, essentially, of a table or plate c having an opening c' , a guide f on said table, having a guiding edge f^3 , a bearing portion f^4 and guiding-flange f^5 , slots c^8 and c^9 in said table or plate c , and a guide at the opposite side of said opening c' , adjustably arranged above said slots, comprising a pair of plates i and j , a pair of guide-plates i' and i^2 having a connecting guiding-surface i^3 , and a post on said plate i^2 for pivotally arranging said guide on the table or plate c , substantially as and for the purposes set forth.
10. The herein-described device or apparatus for forming annular rings of flat metal, consisting, essentially, of a table or plate c having an opening c' , a guide f on said table, having a guiding edge f^3 , a bearing portion f^4 and guiding-flange f^5 , slots c^8 and c^9 in said table or plate c , and a guide at the opposite side of said opening c' , adjustably arranged above said slots, comprising a pair of plates i and j , a pair of guide-plates i' and i^2 having a connecting guiding-surface i^3 , and a post on said plate i^2 for pivotally arranging said guide on the table or plate c , an index-point i^7 , and a scale on said table or plate c , substantially as and for the purposes set forth.
11. The herein-described device or apparatus for forming annular rings of flat metal, consisting, essentially, of a table or plate c having an opening c' , a guide f on said table or plate, and means on said guide for retaining the flat metal strip horizontally in said guide an adjustable guide h , both at one side of said opening, a guide at the opposite side of said opening, said guide being hinged directly to said guide f , and a guide k , all arranged, substantially as and for the purposes set forth.
12. The herein-described device or apparatus for forming annular rings of flat metal, consisting, essentially, of a table or plate c having an opening c' , a guide f on said table or plate, an adjustable guide h , both at one

side of said opening, a guide at the opposite side of said opening, a scale on said table or plate, a guide pivotally connected with said table or plate, an index-point on said guide, 5 means for adjusting said guide, and a guide *k*, all arranged, substantially as and for the purposes set forth.

13. The herein-described device or apparatus for forming annular rings of flat metal, 10 consisting, essentially, of a table or plate *c* having an opening *c'*, a guide *f* on said table, having a guiding edge *f*³, a bearing portion *f*⁴ and guiding-flange *f*⁵, an adjustable guide *h*, both at one side of said opening *c'*, slots *c*⁸ 15 and *c*⁹ in said table or plate *c*, a guide at the opposite side of said opening *c'*, adjustably arranged above said slots, comprising a pair of plates *i* and *j*, a pair of guide-plates *i'* and *i*² having a connecting guiding-surface *i*³, a post 20 on said plate *i*² for pivotally arranging said guide on the table or plate *c*, and a guide *k*, all arranged, substantially as and for the purposes set forth.

14. The herein-described device or apparatus for forming annular rings of flat metal, 25 comprising, essentially, a table or plate *c* having an opening *c'*, a guide *f* on said table, having a guiding edge *f*³, a bearing portion *f*⁴ and guiding-flange *f*⁵, an adjustable guide *h*, both at one side of said opening *c'*, slots *c*⁸ and *c*⁹ in said table and a guide adjustably arranged above said slots, comprising a pair of plates *i* and *j*, a pair of guide-plates *i'* and *i*² having a connecting guiding-surface *i*³, a post 30 on said plate *i*² for pivotally arranging said guide on the table or plate *c*, and said guide having an index-point *i*⁷, a scale on said plate or table *c*, and a guide *k*, all arranged, substantially as and for the purposes set forth.

In testimony that I claim the invention set forth above I have hereunto set my hand this 23d day of April, 1897.

JOHN A. CARLSTEDT.
